UNITED STATES PATENT OFFICE.

SALVATORE GIANDALIA, SON OF ANTONIO, OF AUBURN, ILLINOIS, ASSIGNOR OF
ONE-HALF TO SALVATORE TANI, OF AUBURN, ILLINOIS.

SHOE-POLISHING MACHINE.

1,420,540.

Specification of Letters Patent. Patented June 20, 1922.

Application filed November 25, 1919. Serial No. 340,474.

To all whom it may concern:

Be it known that I, SALVATORE GIANDALIA, SON OF ANTONIO, a subject of the King of Italy, residing at Auburn, in the county of 5 Sangamon and State of Illinois, have invented new and useful Improvements in Shoe-Polishing Machines, of which the following is a specification.

This invention relates to improvements in 10 coin controlled shoe polishing machines.

An object of the invention is the provision of a machine of this character, in which the depositing of the coin will release a pre-determined amount of cleaning liquid, which 15 will be conveyed to the shoes, whereupon a set of brushes will operate over the shoes to clean them and prepare them properly to receive a polish.

Another object of the invention is the provision of a shoe polishing machine having 20 mechanism released by the depositing of an additional coin, to distribute over the surface of the shoes a suitable polishing liquid and to start the operation of polishing 25 brushes, whereupon the surface of the shoes are brought to a bright polish.

Other objects and advantages of the invention will appear as the following description is read in connection with the 30 accompanying drawings.

In the drawings:

Figure 1 is a plan view of the shoe polishing machine embodying the present invention, parts being broken away to show portions of the mechanism.

Figure 2 is a sectional view on the lines 2—2 of Figure 1.

Figure 3 is a section on the line 3—3 of Figure 2.

Figure 4 is a section on the line 4—4 of Figure 2.

Figure 5 is an enlarged detail longitudinal section through the liquid tank and the valves for controlling the flow of liquid from 45 the tank.

Figure 6 is a view similar to Figure 4 but showing the polishing mechanism.

Figure 7 is a detail end elevation of the polishing brushes.

Figure 8 is a longitudinal sectional view 50 of the same showing a shoe in position for polishing.

Figure 9 is an enlarged longitudinal section view through the coin chute.

Figure 10 is a diagram illustrating the

electric wiring for operating the mechanism.

Referring to the drawings in detail, wherein like characters of reference denote corresponding parts, the machine comprises a casing or cabinet which is indicated at 11, 60 and includes independently operated mechanisms, one of which acts to clean the shoes and will be hereinafter referred to as a cleaning mechanism and the other to polish the shoes, being hereinafter referred to as 65 the polishing mechanism. The cabinet 11 is provided with a pair of openings 12 through which the shoes are adapted to be inserted to be acted upon by the cleaning mechanism and positioned adjacent these 70 openings is a chair or seat 13, for the convenience of the person whose shoes are being cleaned. The cabinet is further provided with a pair of openings 14 for the passage of the shoes to be polished, while a chair or 75 seat 15 is also positioned adjacent these openings.

Referring in detail to the cleaning mechanism, the same includes an electric motor 16, which is adapted to drive a crank shaft 17 80 through the medium of worm gearing 18. The shaft 17 is mounted in suitable bearings 19 and is provided with a central crank 20 and connected to this crank is one end of a pitman 21. Pivots connected to the opposite end of the pitman 21 is a block 22 and depending from the bottom of this block is a cross head 23, the latter operating in a longitudinal guide 24. Extending from opposite sides of the block 22 are brushes 25, 90 these brushes being adapted to act upon the inside of the shoes, which are adapted to be positioned upon foot rests and blocks respectively 26 located upon the opposite sides of the guide 24.

The shaft 17 is further provided with cranks 27 located upon opposite sides of the crank 20 and each of which has connected thereto one end of a pitman 28, the opposite end of which is pivotally connected to a 100 block 29. The block 29 is also provided with a cross head 30 similar to the cross head 23 and which operates in a longitudinal guide 31 disposed parallel to the guide 24. The block 29 carries bristles 32, which extends 105 inwardly toward the foot rest or block 26 and as this block is duplicated upon the opposite side of the brushes 25, they are adapted to act upon the outer side of the shoe.

The heels of the shoes are cleaned by means of brushes 33, which are carried by blocks 34 and these blocks are also provided with cross heads 35, which operate in a guide 36 disposed at right angles to the guides 24 and 31. The blocks 34 are connected as shown at 37 and are operated through the medium of a pitman 38, one end of which is pivotally connected to one of the blocks 34 and the opposite end connected to a crank arm 39, which is located at one end of shaft 40. This shaft is mounted in bearings 41 and is driven by bevel gears 42 from the crank shaft 17 at the other end.

In order to provide for shoes of different widths, the guides 31 are pivotally mounted at one end as shown at 43 and are urged inward toward the foot rest 26 through the medium of springs 44. These springs surround short rods 45, which pass through ears 46 and are provided with adjusting nuts 47. The rods 45 pass loosely through openings in the ears 46 so as to provide for proper play when the guides 31 are moved upon their pivots and for this purpose, the connection between the pitman 28 and the crank 27 is also loose. By reference to Figure 4 of the drawings, it will be seen that the arrangement of cranks 20 and 27 are such as to cause the brushes 25 and 32 to move in opposite direction for action upon the inner and outer surfaces of the shoes.

For the purpose of supplying a suitable cleaning liquid to the shoes, there is provided a tank 48, which is located in a compartment 49, the latter being formed by a partition 50 which extends entirely across the top of the machine so as to separate the liquid supplying mechanism from the brushes and their operating mechanism. The machine is designed to supply only a predetermined quantity of fluid at each operation and to accomplish this there is provided a pair of pipes 51, each of which extends downward over a foot rest 26 and terminate in branch pipes 52 of substantially U-shape in plan. These pipes are located directly below the openings 12 and are provided with inwardly extending preferably rubber nipples 53, which are adapted to contact with the shoes, so that the liquid discharged therefrom will be deposited upon the shoes. The pipes 51 are provided with alternately operated valves, the upper valves 54 being located adjacent the tank 48 and being connected by a rod 55 so as to operate in unison. The lower valves 56 are spaced from the valves 54 and a section of the pipe between these valves is so proportioned as to hold only a sufficient quantity of fluid for properly cleaning the shoes. These last mentioned valves, that is the valves 56 are, like the valves 54 connected by a rod 57 to provide for their simultaneous operation.

The valves 54 and 56 are operated by

means of a rotatable member in the form of a disk or cam 58, the latter being mounted upon a shaft 59 which also carries a worm wheel 60. The worm wheel 60 is driven by a worm gear 61 mounted upon one end of a shaft 62 and this last mentioned shaft is driven by a sprocket chain 63, which passes over a sprocket wheel 64 carried by the shaft 62 and extends downward through the partition 50 and engages a sprocket wheel 65 mounted upon the crank shaft 17. Mounted upon the upper end of a short shaft 66, is a spring actuated arm 67, the said arm being pivotally connected to the outer end of a rod 68, which rod is connected to one of the valves 54. The opposite end of the arm 67 has connected thereto an arm 69 and this arm is connected by means of a rod 70 to a pivoted lever 71. One end of the lever 71 is located in the path of movement of a lug 72 which projects outwardly from the periphery of the rotatable member or cam 58, the said lug being upon the same plane as the said member. The rotation of the member 58 will thus operate the valves 54 to bring the openings in these valves in register with the openings in the pipes 51 to permit of the passage of liquid through the valves. The length of the lever 71 is such as to hold the valves in open position for sufficient length of time to permit the proper quantity of liquid to pass therethrough. As this occurs, the valves 56 are in closed position so that the liquid will be trapped between the valves in the pipes 51.

The valves 56 have projecting therefrom a rod 73 and this rod is pivotally connected to a spring actuated arm 74 which is located at the upper end of a short shaft 75. The shaft 75 carries at its lower end an arm 76, which is connected to a pivoted lever 77 through the medium of a rod 78. The lever 77 is located in the path of movement of a lug 79 which is also carried by the rotatable member 58, but is located in a plane above the upper surface of the said member so that the lug 79 will not engage the lever 71 in its movement.

By this means after the liquid has passed through the valves 54 and been trapped within the pipes 51, when the lug 79 engages the lever 77, the valves 56 will be operated to permit the liquid to pass through the openings in these valves, when the said openings register with the openings in the pipes 51, whereupon the liquid will pass downward through the pipes and through the nipples 53 onto the shoes.

For the purpose of starting the operation of the motor 16, a coin is deposited in a slot 80 and during its passage through this slot, the weight of the coin will rest upon a switch member 81, which is pivoted at one end as shown at 82 and forms a portion of the bottom of the slot 80 as illustrated in

Figure 9 of the drawings. When the switch member is depressed, it engages a contact member 83, which is connected by means of a conductor 84 to a magnet 85, the said magnet being connected by a conductor 86 to a battery or other source of electric energy 87. The switch member 81 is connected by a conductor 88 to the opposite side of the battery, so that when the circuit is closed by 10 the weight of the coin the magnet 85 will be energized. This operation will attract an armature 89 which is located in the field of the magnet 85 and will close the circuit in which the motor 16 is included so as to start 15 the operation of the motor. This closing of the motor circuit occurs when the armature 89 engages a contact 90, whereupon current will flow through a conductor 91 connected to the contact and from the battery 87 20 through a conductor 92 which connects the armature with the motor and a conductor 93 which connects the opposite side of the battery with the motor. When the armature 89 has been fully attracted, its end will engage 25 under a spring latch 94, one end of which will be depressed to engage a contact 95, to which is connected a short conductor 96, which is tapped onto the conductor 91 leading from the battery 87. Current will thus 30 pass from the battery 87 through the conductor 91, the conductor 96, the pivoted latch 94, through a conductor 97, which is tapped onto the conductor 92, through the motor 16, the conductor 93 and to the opposite side 35 of the battery 87. The mechanism will thus be operated for a sufficient length of time to properly clean the shoes and when this has been accomplished, the circuit will be broken by means of a lug 98 which extends from the 40 rotatable member 58 in a plane below the lower surface of the same, the arm 99 of the latch 94 being rotated in the path of this lug, whereupon the latch will be operated to release the armature 89 which is moved in a 45 direction away from the magnet 85 under the influence of a spring 100. The circuit will then be broken and the operation of the motor ceased.

After the shoes have been properly 50 cleaned, they are inserted through the openings 14 to be acted upon by the polishing mechanism. This mechanism includes a liquid supply tank 101, having communicating therewith pipes and valves, similar to 55 the pipes 51 and valves 54 and 56 described in connection with the cleaning mechanism. These pipes convey the liquid to the shoes through branch pipes 102 and nipples 103 which are located directly beneath the openings 14.

The brushes for polishing differ from the 60 brushes of the cleaning mechanism and comprise a pair of arched shaped members 104, which are provided with polishing pads 105, 65 the latter being covered by flannel or other

suitable material 106, which is adapted to contact with the surface of the shoe so as to provide the proper luster. The pads 105 are mounted within thin spring metal arches and have pivotally connected thereto one end 70 of pitmans 106, the opposite ends of which are pivotally connected to cranks 107, provided in a shaft 108. This shaft is mounted in suitable bearings 109 and is driven by worm gearing 110 from a motor 111, similar 75 to the motor 16 previously described. The purpose of forming the arch members of resilient material is to permit them to give or expand for shoes of different sizes and to hold the polishing pads 105 in close contact 80 with the shoes. The polishing pads 105 are further provided with pads 112 and these last mentioned pads have connected to their upper surfaces bowed springs 113 and 114. The spring 113 has secured thereto a headed 85 stud 115, which operates in a slot 116 provided in the metallic portions of the brushes 104. The spring 114 has also connected thereto a headed stud 116' which also operates in said slot, but this last mentioned 90 stud has connected thereto one end of a spring 117, whose opposite end is secured to the brush 104 as indicated at 118. The purpose of this is to permit the polishing pad 112 to give upon the inward stroke of the 95 brush 104, the said brush making a complete stroke at each operation of the crank 107, while the pad 112 will only move a distance determined by the size of the shoe being polished.

The brushes 104 have projecting from each side thereof a pair of rods 119 and loosely mounted upon the outer ends of these rods are wheels 120. These wheels revolve in upper and lower opposed U-shaped tracks 105 121, which are mounted in brackets 122 suitably secured within the machine. Mounted upon the rods 119 and interposed between the brushes 104 and the wheels 120, are coil 110 springs 123, the latter acting to center the brushes 104 and to permit of lateral movement in each direction, so as to insure proper contact with the shoes. The brushes 104 serve to polish the toe and both sides of the 115 shoes and for this purpose of polishing the heels, there is provided brushes 124, which are provided with polishing pads similar to the pads 105, the said brushes being guided in the tracks 121 and being maintained in proper position through the medium of the 120 rods 125 and the springs 126. The brushes 124 are operated by means of pitmans 127, which are connected to cranks 128. These cranks are formed in a shaft 129 which is driven by means of a shaft 130 and bevel 125 gearing 131.

The polishing mechanism is operated in the same manner as the cleaning mechanism previously described, that is by the insertion of a coin in a slot 132, which coin operates 130

in the manner previously described to energize a magnet and close the motor circuit for the operation of the motor and the rotatable member for the operation of the valves for supplying the polishing liquid. It is therefore not thought necessary to repeat the description of this mechanism.

The coin from the slot 80 is deposited in a coin receptacle or drawer 133, while the coin from the slot 132 is deposited in a similar receptacle or drawer 134. Suitable normally closed filling openings 135 and 136 are provided for filling the tanks 48 and 101 respectively.

15 It is believed that when the foregoing description is read in connection with the accompanying drawings, the construction, operation and advantages of the invention will be apparent and that further description is therefore unnecessary. The invention is susceptible of various changes in its form, proportions and minor details of construction, and the right is herein reserved to make such changes as properly fall within the 25 scope of the appended claims.

Having described the invention what is claimed is:—

1. The combination with a shoe polishing machine including brushes and means for 30 operating the brushes, of a liquid reservoir, pipes for conveying liquid from the reservoir to a point adjacent the brushes, spaced alternately operated valves located in said pipes for controlling the amount of liquid 35 delivered from the reservoir and means operated by the brush operating means for controlling the operation of the valves.

2. The combination with a shoe polishing machine including brushes and means for operating the brushes, of a liquid reservoir, 40 pipes for conveying liquid from the reservoir to a point adjacent the brushes, flexible discharge nipples for said pipes, valves for controlling the amount of liquid discharged from the reservoir and means operated by 45 the brush operating means for controlling the operation of the valves.

3. The combination with a shoe polishing machine including brushes and means for operating the brushes, of a liquid reservoir, 50 pipes for conveying liquid from the reservoir to a point adjacent the brushes, spaced alternately operated valves located in said pipes for controlling the amount of liquid delivered from the reservoir and means including a rotary member operated by the brush operating means for controlling the 55 operation of the valves.

4. The combination with a shoe polishing machine including brushes and means for 60 operating the brushes, of a liquid reservoir, pipes for conveying liquid from the reservoir to a point adjacent the brushes, spaced alternately operated valves located in said pipes for controlling the amount of liquid 65 delivered from the reservoir, a rotary lug carrying member and means including a pivoted lever located in the path of the rotary lug carrying member for controlling the operation of the valves.

In testimony whereof I affix my signature.

SALVATORE GIANDALIA, SON OF ANTONIO.
